UNITED STATES PATENT OFFICE

114,894

DESIGN FOR A DISPENSING MACHINE CABINET

Ameen B. Hassan, Paris, Tex.

Application February 7, 1939, Serial No. 82,847

Term of patent 7 years

To all whom it may concern:

Be it known that I, Ameen B. Hassan, a citizen of the United States, residing at Paris, in the county of Lamar and State of Texas, have invented a new, original, and ornamental Design for a Dispensing Machine Cabinet, of which the following is a specification, reference being had to the accompanying drawing, forming part thereof.

I claim:

The ornamental design for a dispensing machine cabinet, as shown.

AMEEN B. HASSAN.
